UNITED STATES PATENT OFFICE.

HAROLD W. SHONNARD, OF NEW YORK, N. Y., ASSIGNOR TO CRUCIBLE STEEL COMPANY OF AMERICA, OF PITTSBURGH, PENNSYLVANIA, A CORPORATION OF NEW JERSEY.

AUTOMOBILE TORPEDO.

1,163,607.

Specification of Letters Patent.

Patented Dec. 7, 1915.

Original application filed April 3, 1915, Serial No. 18,962. Divided and this application filed April 3, 1915.
Serial No. 18,963.

To all whom it may concern:

Be it known that I, HAROLD W. SHONNARD, residing at Far Rockaway, Queens borough, city and State of New York, a citizen of the United States, have invented or discovered certain new and useful Improvements in Automobile Torpedoes, of which improvements the following is a specification.

10 In my application Serial No. 18,962, filed of even date herewith, I have illustrated and described certain improvements in gyroscopes for automobile torpedoes, such improvements being particularly adapted to 15 carry out the method of fire control for torpedoes covered in my United States Patent No. 1,035,647. Among the various features of construction shown in said application, there are instrumentalities for completing an electric circuit through the walls 20 of a torpedo and a launching tube, and between conductors within the torpedo and a source of electrical supply outside of such tube. While means to such end form a part 25 of the invention claimed in said application, they are not specifically claimed therein but in my present application.

It is, therefore, the object of my present invention to provide torpedoes and their 30 launching tubes with adequate means for carrying an electric circuit through their walls, and to provide means for breaking such a circuit to permit the launching of the torpedo.

35 My invention broadly considered is unlimited to any specific purpose for which the current is used within the torpedo. In the embodiment illustrated herein it is used to excite the inductor of an electric motor 40 gyroscope, but it will be readily understood that it may be used for any other desired purpose.

In the accompanying sheets of drawings, wherein my invention is illustrated, Figure 45 1. is a transverse sectional view through a portion of a launching tube and a torpedo placed therein, the plane of view being indicated by the broken line I—I, Fig. 3; Fig. 2 a bottom plan view of the casing shown 50 immediately above it in Fig. 1; and Fig. 3 a sectional view taken on the line III—III,

Fig. 1, a portion of the gyroscope housing being shown in elevation.

While in the practice of my invention there may be as many conducting paths as 55 desired through the launching tube and torpedo walls, as shown herein three paths are provided, they being intended to carry a three phase alternating current.

Referring to the drawings the torpedo 60 wall 1 is provided with an opening adjacent to which there is an inwardly extending boss 2. To this boss there is secured, by a water tight joint, a disk 3 provided with three separately insulated conducting posts 65 4, the outer ends of which are substantially flush with the face of the disk 3, their inner ends being provided with binding screws 5.

To the outer wall of the launching tube 32 there is attached a substantially cylindrical casing 6, having a cover 7, and provided with a reciprocatory piston 8, having as a part thereof a tubular stem 9 movable through the cover 7. The piston is held 75 yielding toward the torpedo by means of a spring 10, and is provided with three separately insulated brushes 11 adapted to contact with the posts 4. The brushes are slidably mounted in the piston head and are backed by suitable springs 12, which bear 80 at their opposite ends against conducting plugs 13. Electrical continuity may be established between the brushes 11 and the plugs 13 either through the springs 12, or through flexible conductors 14. The outer 85 ends of the plugs 13 are provided with binding screws 15 for the attachment of supply conductors 16 which extend through the tubular stem 9 of the piston.

The circuit may be broken by moving the 90 piston 8 outwardly, and this may be done manually, as by engaging a handle 17 attached to the stem 9, or by compressed air let into the casing 6 at the rear of the piston shoulder 18 through a conduit 19. This 95 conduit may, as shown in my above mentioned application, lead from the passageway connecting the storage reservoir with the launching tube. To retain the piston in its retracted position, the stem 9 thereof 100 may be provided with a notch 20 adapted to receive a latch 21 pivotally mounted on

the cover 7 and held yieldingly toward the stem by a spring 22.

As already stated, the current led into the torpedo through its wall and that of the launching tube may be used for any desired purpose, as for example the spinning of a gyroscope. The construction of the gyroscope shown herein, and the leads for making and breaking a circuit through its gimbal 10 ring, are fully described in my above mentioned application, and therefore need not be explained herein. It is only necessary to state that conductors 23 lead from the posts 4 to plugs 24 carried by a supplementary 15 casing 25, and that suitable electrical connections are made between such plugs and brushes 26 carried by a member 28 slidably mounted in such casing. When in the positions indicated in Fig. 3, these brushes are 20 in contact with contactors 29, from which conductors 30 lead to the inductor of the electric motor gyroscope mounted within the casing 31.

In operation, before placing the torpedo 25 1 within the launching tube 32 the piston 8, if not in its rearward position, may be withdrawn by engaging the handle 17. After placing the torpedo in the tube and adjusting it so that the disk 3 registers with the 30 piston 8, the latch 21 may be released to permit the spring 10 to press the piston inwardly. Contact will then be established between the posts 4 and the brushes 11, such brushes being pressed against the posts by 35 means of the springs 12. Before launching the torpedo the piston will of course be withdrawn, either by pulling the handle 17, or by means of air let into the casing through the pipe 19.

40 I claim as my invention:

1. An automobile torpedo having an opening through the wall thereof, a closure for such opening, and electrical conducting elements carried by said closure and having 45 contact portions exposed at the outer face thereof.

2. An automobile torpedo provided internally with electrically operated mechanism and having an opening through its wall, a 50 closure for such opening and electrical conducting elements carried by said closure and having contact portions exposed at and terminating with the outer face thereof, and electrical connections between said contact 55 elements and said mechanism.

3. The combination of a torpedo launching tube, an automobile torpedo therein, electrical conducting elements borne respectively by the walls of said tube and torpedo 60 and adapted to contact with each other, and

means for moving the conducting elements of one of said walls to make and break a circuit.

4. The combination of a torpedo launching tube, an automobile torpedo therein and 65 provided internally with electrically operated mechanism, electrical connections extending from such mechanism through the wall of the torpedo and terminating with exposed contact faces at the outside of the 70 torpedo, and movable conducting elements borne by the launching tube and adapted to contact with said first named elements.

5. A launching tube for an automobile 75 torpedo provided with an opening through its wall, and a member movable through such opening and provided with electrical conducting elements adapted to close a circuit through the wall of a torpedo.

6. A launching tube for an automobile 80 torpedo provided with an opening through its walls, a casing secured to such wall adjacent to said opening, and a member mounted for reciprocation within said casing and provided with electrical conducting ele- 85 ments adapted to close a circuit through the wall of a torpedo.

7. A launching tube for an automobile torpedo provided with an opening through its wall, a casing secured to such wall adjacent to said opening, a reciprocatory member within said casing held yieldingly toward the interior of the launching tube, and electrical conducting elements borne by said member and having exposed contacting 95 faces on the inner side thereof.

8. A launching tube for an automobile torpedo provided with an opening through its wall, a casing secured to such wall adjacent to said opening, a reciprocatory mem- 100 ber within said casing held yieldingly toward the interior of the launching tube, and spring-pressed electrical conducting brushes borne by said member.

9. A launching tube for an automobile 105 torpedo provided with an opening through its wall, a casing secured to such wall adjacent to said opening, a piston movable with- in said casing and held yieldingly toward the interior of the launching tube, electrical 110 conducting elements borne by said piston and having contact faces at the inner end thereof, and means for holding said piston in its outward position.

115 In testimony whereof I have hereunto set my hand.

HAROLD W. SHONNARD.
